UNITED STATES PATENT OFFICE.

FRED EVANS, OF SUMMIT, NEW JERSEY, ASSIGNOR, BY MESNE ASSIGNMENTS, TO VOICES INCORPORATED, A CORPORATION OF DELAWARE.

TALKING TOY MECHANISM.

Application filed March 21, 1923. Serial No. 626,496.

This invention relates to sound producing devices more particularly such as are used in toys, and it is herein intended to devise a sound producing mechanism for use in talking dolls.

One object of this invention is to provide a sound producing device of the class described, which will emit a sound closely simulating the cry of a child, and which at the same time may be cheaply constructed, and rugged enough to withstand the rough usage to which such devices are ordinarily subjected.

Another object of the invention is to provide a sound producing mechanism of the class described, which is provided with improved means by which the sound emitted may be controlled.

Further and more specific objects, features and advantages will more clearly appear from the detail description below taken in connection with the accompanying drawing which forms a part of this specification.

In the accompanying drawing, wherein I have shown a preferred form of embodiment of my invention:

Figure 1 is a vertical cross-sectional view of the device with parts being broken away; and

Figure 2 is a bottom plan view of the device.

Fig. 3 is a cross-section of the casing on the broken line 3—3 of Fig. 1, showing the slot in the weight in operative engagement with the revolute twisted strip.

Referring now to the drawing, wherein similar reference characters refer to similar parts in both views thereof, the reference character 1 designates a casing, constructed preferably of cardboard, fibre, or other light material. In one end of this casing is a head 2, and mounted intermediate the ends of the casing, which will be preferably of cylindrical form, is a second head 3, the latter being spaced inwardly from the open end of the casing. The head 3 has a smooth outer face, but its inner face is channeled, as at 4, so that the edge 5 of a bellows 6 may be mounted in place thereon by causing this edge to overlie the channel wherein it is held by means of a spring-ring 7.

The bellows is of an air-proof material, such as a treated fabric, and as is indicated in Figure 1, is circumferentially creased so that it may be readily collapsed. Mounted

on the upper end of the bellows is a disc 8, this disc being made of a heavy material, such as lead. The head 3, it will be noted, is provided with an aperture 9, extending therethrough and overlying this aperture is a chamber 10, in which is mounted a reed 11, this reed being so positioned that upon the descent of the disc 8, so as to cause the bellows to collapse, the expelled air will cause the reed to vibrate and give off a sound.

The outer end of the reed projects into a chamber 12, provided with an orifice 13, this chamber 12 together with its orifice, constituting the means by which the sound is regulated and the enunciation of distinct syllables produced.

Mounted centrally in the head 2, is a pin 14, to the inner end of which is attached a strip or rod of metal 15, this strip being twisted to form a cam screw having a spirally twisted cam face of large pitch. The strip 15 extends through the disc 8, which is provided with a narrow cam slot fitting the strip 15 fairly closely. At the lower end of the strip there is mounted thereon a rod 16 which projects through the head 3, and the orifice chamber, a circular disc 17 being mounted on the outer end of the rod 16, this disc being of such diameter as to overlie the orifice 13.

The disc 17, as will be noted on reference to Figure 2, is provided with ports 18 and 19, the first being circular, and the second somewhat elongated. These ports are positioned in the disc so that as the disc rotates, as will later be explained, the ports will come successively in registry with the orifice 13 opening into the orifice chamber.

The operation of the device will now be explained. It will be understood that these "voices" are to be used within the body of a talking toy, such as a doll, wherein they are concealed from view. The voice is to be so positioned within the doll that as the body of the doll is moved, for instance to the reclining position, the voice will give off a cry, or a series of cries. Assuming the doll is to give its cry when moved to the reclining position the voice will be so disposed within the body of the doll, that when this change in position occurs, the ports will be as indicated in Figure 1. The weighted disc 8 will be seen to be in the upper end of the casing, and the bellows

fully distended. The weight 8 will now be free to move downwardly under the influence of gravity, and as it descends it will expel air from the interior of the bellows; this blast striking the reed and causing it to vibrate. As the weight descends, the slot therein, through which the strip 15 passes, will cause the strip to untwist, this resulting in a rotation of the pin 16, and a movement 10 of the disc 17.

When the downward movement of the disc 8 is beginning, the ports 18 and 19 in the disc 17 will be out of registry with the orifice 13, the air passing through the aperture in the head and through the reed, will thereupon pass into the orifice chamber, but as the orifice is closed this air will simply be compressed, and any sound produced by the reed will be muffled.

During the descent of the weight, however, the rotation of the pin 16 produced by the untwisting of the strip 15, will bring the port 18 into registry with the orifice 13, whereupon the air expelled from the bellows will pass outwardly to the atmosphere, this causing a distinct sound to be given off by the reed. The continued downward movement of the weight now causes the port 18 to pass out of registry with the orifice 13, whereupon the sound will again be muffled until the port 19 registers with the orifice, whereupon a second sound will be produced by the reed.

This action of permitting the reed to sound, and then muffling it, then permitting it to sound freely a second time, produces distinct syllables, which closely simulate the pronunciation of "ma-ma", it being understood that a suitable reed is chosen so as to give a thin wailing cry. It is obvious that instead of producing a two-syllable cry, as is here described, the disc 17 may be provided with a plurality of apertures, and that the size of these apertures may be regulated so as to change the character and number of the syllables produced by the voice.

When the weight 8 has moved to its limit of downward travel, completely expelling the air from the bellows, the reed will cease sounding, but upon movement of the doll to the upright position, the weight will again move under gravity to its limit of upward travel to the position indicated in Figure 1, whereupon the cycle of operations may be repeated.

In the distension of the bellows the air drawn inwardly through the orifice chamber, and through the reed, will produce no sound, since the reed is here disposed in such a way that passage of air into the interior of the bellows will force the reed from its seat and prevent vibration.

It has been noted that the head 3 is placed inwardly from the end of the casing, and the purpose of this construction is to in-

sure that the sound regulating and producing parts which are here mounted on the outer face of the head 3, will be protected by the extending walls of the casing.

The parts of which the device are made 70 may be constructed of cheap material, and the labor caused in assembling is relatively small. There are no parts which are of delicate character and the device is so arranged that the working parts are protected. 75 Such a sound producing mechanism is capable of use for an indefinite period, inasmuch as there is no working part which will readily wear out.

It will be seen that while the device here 80 illustrated will produce a "ma-ma" sound, various other sounds may be given off if desired, it being simply necessary to change the sound regulating disc.

As many changes could be made in this 85 construction without departing from the scope of the following claims, it is intended that all matter contained in the above description or shown in the accompanying 90 drawing shall be interpreted as illustrative 95 only and not in a limiting sense.

Having thus described my invention what I claim as new and desire to secure by Letters Patent is:

1. A device of the class described having 95 in combination, a collapsible bellows, a sound reed operated thereby, means having an opening through which the sound from the reed may issue, a valve rotatably mounted with respect to said opening and means having a spiral cam face for rotating said valve to control the issuance of sound from said opening as the bellows is operated.

2. A device of the class described having 100 in combination, a casing, a collapsible bellows therein having two heads, one fixed with respect to the casing and the other a weighty head movable back and forth in the casing to collapse and distend the bellows by gravity, a sound reed actuated by 105 said bellows, means carried by one of said heads and having an orifice through which the main sound from said reed will escape, a valve rotatably mounted with respect to one of said heads and acting to open and 110 close said orifice and means for actuating said valve during that movement of the bellows which causes the reed to sound, said last mentioned means comprising a twisted cam rod acting to rotate said valve during 115 the actuation of the bellows which causes the reed to sound.

3. A device of the class described, comprising in combination, a casing, a head mounted intermediate the ends thereof, a 120 bellows attached to one face of said head, a weight mounted on said bellows and held thereby against rotative movement, the said weight provided with a slot, a reed chamber on the other face of said head, in com- 125

5 munication with the interior of said bellows, an orifice chamber into which said reed projects, a revoluble twisted member extending through the slot in said weight, a disc pro-
5 vided with ports attached to the end of said twisted member, said disc being applied to the orifice of the said chamber to open and close the said orifice and adapted to be rotated by the twisted member during the descent of said weight, whereby to bring said ports successively into registry with said orifice.

4. A device of the class described, comprising a casing, having a closed end, a head intermediate the ends of said casing, a bellows attached to one face of said head, a weight mounted on said bellows, a chamber provided with a reed mounted on the other face of said head in communication with the interior of said bellows, a chamber provided with an orifice mounted adjacent said reed chamber and in communication with said reed, a twisted strip attached to the closed end of said casing, and extending through said disc and said bellows, a disc provided with ports attached to the end of said strip, the walls of the aperture in said weight through which said strip extends being so designed as to cause a rotation of the end of said strip as said bellows is collapsed, whereby to rotate said disc and bring said ports successively in registry.

5. A device of the class described, comprising a cylindrical casing having a closed end, a head mounted within said casing intermediate the ends thereof, the bellows attached to one face of said head, a weight attached to the end of said bellows, a chamber having a reed projecting through the wall thereof, said chamber being mounted on the outer face of said head in communication with said bellows, an orifice chamber mounted adjacent said reed chamber in communication with said reed, a twisted strip attached to the closed end of said casing and projecting through said bellows and said weight, a disc provided with ports, on the other end of said strip, adapted to overlie said orifice, the walls of the aperture of said weight through which said strip extends being so designed as to cause a rotation of said strip and said disc, as said weight collapses said bellows, whereby to bring said ports successively into registry with said orifice.

6. A device of the class described having in combination a bellows, a sound reed operated thereby, means having an orifice through which the sound from said reed may escape, a valve rotatable over the face of said orifice to open and close the same, and a twisted cam rod acting responsive to operation of the bellows to rotate said valve during actuation of the bellows to cause the reed to sound.

7. A device of the class described having in combination, a casing, a collapsible bellows therein having two heads, one fixed with respect to the casing and the other a weighty head movable back and forth in the casing to collapse and distend the bellows by gravity a sound reed actuated by said bellows, means carried by one of said heads and having an orifice through which the main sound from said reed will escape, a valve rotatably mounted with respect to one of said heads and acting to open and close said orifice and means for actuating said valve during that movement of the bellows which causes the reed to sound, and so said last mentioned means comprising a twisted cam rod acting to rotate said valve during the actuation of the bellows which causes the reed to sound and said rod being fixed to said valve and said weighty head having a cam opening therein through which the rod passes to operate the latter as the weighty head moves in the casing.

8. A device of the class described having in combination, a bellows having two heads, one of said heads being a weighty head whereby the same will act to operate the bellows by gravity, a sound reed operated by the bellows, means having an opening through which the sound from the reed may issue, a valve rotatably mounted with respect to said opening and means having a spiral cam face to cause rotation of said valve to control the issuance of sound from said opening, said valve being thus operated by the operation of the bellows by said weighty head.

9. A device of the class described having in combination, a bellows having two heads, one of said heads being a weighty head whereby the same will act to operate the bellows by gravity, a sound reed operated by the bellows, means having an opening through which the sound from the reed may issue, a valve rotatably mounted with respect to said opening and means including a spirally twisted cam member along which the weighty head slides to cause rotation of said valve to control the issuance of sound from said opening, said valve being thus operated by the operation of the bellows by said weighty head.

10. A sound producing device having in combination, a weighty head and a fixed head, a tubular bellows connecting said heads and adapted to be operated by gravity by said weighty head, a sound reed operated by the bellows, means having an opening through which the sound from the reed is adapted to issue, a valve rotatably and slidably mounted with respect to said opening, and means including a cam member cooperating with said weighty head to automatically cause rotation of the valve to control the issuance of sound from said sound opening.

responsive to the operation of the bellows.

11. In a sound producing device, a collapsible air chamber, a sound reed operated thereby, means having an opening through which the sound from the reed issues, a valve rotatably mounted with respect to said opening, and spiral cam means acting to cause rotation of the valve to control the issuance of sound from said opening responsive to the operation of said collapsible air chamber, said cam means comprising a twisted rod extending through the air chamber.

12. A sound producing device having in combination, a weighty head and a fixed head, a tubular bellows connecting said heads and adapted to be operated by gravity by said weighty head, a sound reed operated by the bellows, means having an opening through which the sound from the reed is adapted to issue, a valve rotatably and slidably mounted with respect to said opening

and a cam member operating responsive to the movement of said weighty head to automatically cause rotation of the valve to control the issuance of sound from said sound opening. 25

13. A sound producing device including an air chamber having a fixed head and a weighty head movable by gravity towards and from the fixed head, a sounding reed operated by the passage of air in the movement of the weighty head and associated with a sound escape opening, a valve rotatably and slidably mounted with respect to said opening, and cam means responsive to the gravity movement of said weighty head and operatively engaged with said valve to automatically effect rotation of the valve to control the issuance of sound from said escape opening. 30 35 40

In testimony whereof, I affix my signature.

FRED EVANS.
